CONTROL MECHANISM FOR MOVING-PICTURE APPARATUS

William W. Blakesley, Brattleboro, Vt.

Application April 2, 1931. Serial No. 527,237

3 Claims. (Cl. 88—16.2)

This invention relates to mechanism for controlling the operation of motion-picture apparatus under the usual operating conditions in which two projecting machines are used alternately.

5 It is the general object of my invention to provide mechanism by which two projecting machines may be conveniently controlled from a single operating station or from one or more additional stations.

10 A further object of the invention is to provide mechanism by which the motors, the sound apparatus and the shutters of two projecting machines may be conveniently controlled and operated in the desired sequence by the use of a single operating or control device.

My invention further relates to arrangements and combinations of parts which will be herein-after described and more particularly pointed out in the appended claims.

20 A preferred form of my invention is shown in the drawings, in which

Fig. 1 is a front elevation of my improved control apparatus;

Fig. 2 is an enlarged front elevation of an index plate;

Fig. 3 is a front view of my improved control mechanism with the cover removed and with the control circuits indicated diagrammatically;

Fig. 4 is a sectional side elevation of the control mechanism;

Fig. 5 is a detail sectional view, taken along the line 5—5 in Fig. 3;

Fig. 6 is a detail sectional view, taken along the line 6—6 in Fig. 5;

35 Fig. 7 is a detail sectional view, taken along the line 7—7 in Fig. 3;

Fig. 8 is a detail sectional view, taken along the line 8—8 in Fig. 4, and

40 Figs. 9 to 15 are diagrammatic views showing successive settings of the control mechanism.

Referring to the drawings, I have shown a control mechanism M (Fig. 1) having an operating lever 20 and an index plate 21. Additional operating levers 22 may be mounted at additional

45 operator's stations and may be connected by a link 24 to the control lever 20. Each additional operating lever 22 is preferably provided with an index plate 25 identical with the main index plate 21. It will be obvious that the number of operating stations may be increased as desired.

In the usual operation of commercial motion-picture apparatus, two projecting machines are provided, each having its own motor, its own sound apparatus and its own shutter device. The 55 two projecting machines are used alternately for

successive reels of film in a multi-reel picture, and my improved control apparatus is designed particularly to facilitate the change-over from one machine to the other.

The usual procedure at the change-over is substantially as follows:

Assume that two machines A and B are provided and that the A machine is in operation, with the end of the film approaching. The operator starts the motor of the B machine, which has been already loaded with the next succeeding film. When the B machine is up to speed, the exposure and sound-control are shifted to the B machine but the A machine is allowed to run until the end of the preceding film has been wound off. The A machine is then stopped and reloaded. When the end of the film in the B machine is approaching, the A machine is started up and the cycle of operations is repeated. By the use of my improved apparatus, all of these successive conditions of operation are attained by the use of the single control lever 20.

I will first describe the details of construction of the apparatus and will then describe the operation thereof.

Referring particularly to Figs. 3 and 4, my improved control apparatus comprises a box or casing 30 having a cover 31 closely fitting the casing 30 and secured thereon by friction or in any convenient manner.

85 The control lever 20 is provided with an opening 33, in which a headed stud 34 may be retained by a set-screw 35. The stud 34 is inserted from the rear through an opening 36 in the cover 31 and forms a journal for the control lever 20. A spring plunger 38 is slidable in a recess 39 in the upper end of the lever 20 and may be keyed or otherwise held from angular movement therein. The end of the plunger 38 is beveled to enter the enlarged ends of a series of notches or index points numbered 1 to 8 inclusive in Figs. 2 and 8. The spring plunger 38 acts to yieldingly retain the lever 20 in alignment with any selected notch or index point.

95 A supporting member is mounted in the casing 30, said member being preferably built up as indicated in Fig. 4, with two discs 40 and 41 and two rings 42 and 43, all of non-conducting material and firmly secured together by bolts 45 to form a non-conductive support for a series 100 of contact members.

105 Each contact member preferably comprises a sheet of suitable conducting metal, such as copper or brass, bent to a U-shaped section, as indicated at 50 in Fig. 5, and having the end por-

tions 51 bent outward to facilitate the entrance of the movable contact member. These contact plates 50 may be secured between the rings 42 and 43 by bolts 53 which may also constitute 5 terminals to the rear ends of which the various connecting wires may be secured.

A non-conducting plate or disc 60 (Fig. 4) is mounted on a stud 61 and may be secured against a shoulder 62 thereof by a lock nut 63. 10 The stud 61 is rotatable in a bearing opening in the plates 40 and 41 and is provided with a head 64 engaging the rear face of the plate 40.

A cross-pin 65 in the stud 61 is received in a corresponding slot in the disc 60 and provides 15 a driving connection therefor. A cross-pin 66 is also secured in the stud 61 near the outer end thereof and is received in a slot or recess 67 in the inner end of the lever stud 34 previously described. This pin and slot connection between 20 the control lever 20 and the stud 61 permits removal and replacement of the cover 31 without changing the adjustment or relation of any operating parts.

A contact ring 70 is secured to the disc or 25 plate 60, as by screws 71 (Fig. 3), and is provided with projecting contact arms *a*, *b*, *c* and *d*.

As the plate 60 and contact ring 70 are turned angularly, the contact arms *a*, *b*, *c* and *d* enter 30 between the spaced parts of the U-shaped contact members 50 and complete circuits therethrough. Successive contact members 50 are designated 50^a to 50^f inclusive in Fig. 3.

Diagrammatic connections for the several devices are indicated in Fig. 3 as follows:—

35 Power is taken in over line wires 80 and 81, the wire 80 being connected to a common return plate 82, to which one side of each motor and of each sound and shutter control device is connected. The second line wire 81 is connected 40 through a flexible wire 83 to the movable contact ring 70.

The motor M for the A machine is connected to the common return plate at 84 and through a terminal 85 and a wire 86 to the contact member 45 50^a. The motor M' for the B machine is similarly connected to a terminal 87 on the return plate 82 and through a terminal 88 and wire 89 to the contact member 50^b.

The sound mechanism 90 of the A machine 50 is connected to a terminal 91 and the sound mechanism 92 of the B machine is connected to a terminal 93. A switch 94 is connected by a wire 95 to an amplifier 96 which is connected through a common return wire 97 to the sound 55 mechanisms 90 and 92. The switch 94 is movable into contact with the terminal 91 or the terminal 93 by one or the other of a pair of magnets 100 and 101.

The magnet 100 for the A machine is connected 60 to a terminal 102 on the common return plate 82 and through a terminal 103 and wire 104 to the contact member 50^a. The magnet 101 for the B machine is connected to a terminal 105 on the return plate 82 and is also connected through a 65 terminal 106 and wire 107 to the contact member 50^b.

When the A machine is in use and the A magnet 100 is energized, the switch 94 will be moved to engage the contact 91, thus connecting the 70 sound mechanism 90 of the A machine to the amplifier 96. Similarly, when the B machine is in use, the magnet 101 will move the switch 94 against the contact 93, thus connecting the sound mechanism 92 of the B machine with the amplifier 96.

A shutter 110 is provided for the A machine and a shutter 111 for the B machine. These shutters are provided with depending arms 112 and 113. The arm 112 is controlled by one or the other of a pair of magnets 114 and 115, and the arm 113 is controlled by one or the other of a pair of magnets 116 and 117.

The B magnets 114 and 116 are in series and when these two magnets are energized, the shutter 110 will be moved upward to cut off the light from the lens of the A machine, while the shutter 111 will be moved downward to inoperative or open position and the picture is projected from the B machine. Similarly, when the A magnets 115 and 117 are energized, the shutter 110 will be moved downward to the full line inoperative position shown in Fig. 3, and the shutter 111 will be moved upward to cover the lens of the B machine.

The B magnets 114 and 116 are connected by a wire 120 to a terminal 121 on the return plate 82 and by a wire 122 through a terminal 123 and wire 124 to the contact member 50^d. Similarly, the A magnets 115 and 117 are connected by a wire 130 to a terminal 131 on the return plate 82 and by a wire 132 through a terminal 133 and wire 134 to the contact member 50^c.

It will be noted that the shutter-operating magnets 114 and 116, or 115 and 117, are connected in series, so that the shutters 110 and 105 111 are operated together, one shutter moving to operative position and the other to inoperative position simultaneously.

Signal lights are provided for the purpose of giving a visual indication of the machine to 110 which the sound amplifier is connected and in which the shutter is withdrawn or open. For this purpose, a signal light 140 is connected in the wire 107 to the contact member 50^f, a light 141 is connected in the wire 104 to the contact 115 member 50^e, a light 142 is connected in the wire 124 to the contact member 50^d, and a light 143 is connected in the wire 134 to the contact member 50^c. Whenever a circuit is completed through any one of these wires, the corresponding signal light will be illuminated. The lights 141 and 143 for the A machine may be of a different color from the lights 140 and 142 for the B machine.

Having described the details of construction 125 of my improved control mechanism, I will now describe the successive steps in the operation thereof.

The movable contact ring 70 is shown in Fig. 3 in a position corresponding to the #2 position of the lever 20 in Figs. 1 and 2, that is—with the spring plunger 33 centered in #2 notch, corresponding to the off-position in which neither machine is operating. It will be noted that in this position the projecting contact arms *a*, *b*, *c* and *d* are all out of register with the contact members 50^a to 50^f.

If it is desired to warm up the B motor or to run the B motor for inspection or testing, the lever 20 is moved to the #1 notch, (Fig. 3), moving the contact ring 70 to the position shown in Fig. 9, in which position the contact arm *b* engages the contact member 50^b, completing the power circuit through the motor M' of the B machine. The other contact arms *a*, *c* and *d* are out of contact with any contact member in this #1 position.

Assuming now that the machines are to be placed in operation, the lever 20 is moved to the #3 notch and the ring 70 assumes the position 150

shown in Fig. 10. The contact arm *a* engages the contact member 50^b, causing the motor M' of the B machine to start up or to continue in operation. The contact arm *c* engages the contact member 50^f, which causes the sound mechanism 92 of the B machine to be connected to the amplifier 96 and also illuminates the signal light 140, indicating that the amplifier is connected to the B machine.

10 The contact arm *d* also engages the switch plate 50^d, which causes the B magnets 114 and 116 (Fig. 3) to be energized, with resultant movement of the A shutter to operative position and the B shutter to inoperative or open position, thus rendering the B machine fully operative. Engagement of the contact arm *d* with the contact member 50^d also illuminates the light 142, indicating visually that the B shutter is open. The B machine is thus fully operative, while the

20 A machine remains at rest.

As the end of the film approaches in the B machine, the control lever 20 is shifted to the #4 notch, moving the contact ring 70 to the position shown in Fig. 11. In this position the contact arms *a*, *c* and *d* engage the contact members 50^b, 50^f and 50^d as at the #3 position shown in Fig. 10 and the B machine remains fully operative. At the same time, however, the additional contact arm *b* engages the contact plate 50^a which 30 completes the circuit through the motor M of the A machine and thus starts the A motor in operation.

The control lever 20 is then shifted to the #5 notch and the contact ring 70 is thereby moved 35 to the position shown in Fig. 12, in which it will be seen that the contact arms *a* and *b* still engage the contact members 50^b and 50^d but that the contact arms *c* and *d* have shifted from the contact members 50^f and 50^d to the contact members 50^e and 50^e. Such shifting of the contact arm *c* from the contact member 50^f to the contact member 50^e causes reversal of the sound control switch 94 (Fig. 3) and connects the amplifier 96 with the sound mechanism 90 of the A machine. Similarly, shifting of the contact arm *b* from the contact member 50^d to the contact member 50^e causes the A magnets 115 and 117 (Fig. 3) to be energized, moving the shutters to the full line position shown in Fig. 3, with the A shutter 50 inoperative and open and with the B shutter 110 operative to shut off projection from the B machine.

When the end of the film in the B machine has 55 been wound off, the control lever 20 is shifted to the #6 notch, moving the contact ring 70 to the position shown in Fig. 13, in which the contact arms *b*, *c* and *d* remains in contact with the contact members 50^e, 50^e and 50^e as shown in Fig. 12, continuing the A machine in full operation, 60 while the contact arm *a* moves out of engagement with the contact member 50^b, thus stopping the motor M' of the B machine.

In the usual continued operation of motion-picture apparatus, the movement of the lever 20 65 will now be reversed, returning through the #5 and #4 positions to the #3 position and then again reversing the direction of lever movement. In other words, the notches or index points #3, #4, #5 and #6 constitute the usual operating 70 points and the lever 20 is moved successively back and forth between point #3 and point #6.

If, however, it is desired to stop both machines 75 after a film has been run off in the A machine, the control lever 20 may be moved to the #7 notch, bringing the contact ring 70 to the position shown

in Fig. 14, in which all of the contact arms *a*, *b*, *c* and *d* are out of contact with any of the contact plates 50^a to 50^e.

If it is now desired to start up the motor M of the A machine for any purpose, the control lever 80 may be shifted to the #8 notch, bringing the parts to the position shown in Fig. 15, with the contact arm *a* in engagement with the contact member 50^a which controls the motor M of the A machine.

I have thus provided a single control lever and 85 switch mechanism by which the motors, the sound connections and the projection or exposure of two projecting machines may be conveniently controlled from any one of a plurality of stations by successive movements of a control lever 20 or 22, back and forth over a series 90 of operating positions indicated by the notches or index points in the index plates 21 or 25. At the same time, the lights 140 to 143 indicate which machine is in operation as to sound and 95 projection.

I am thus able to perform the necessary successive steps of the change-over from one projecting machine to the other in a very simple manner, and I avoid liability to mistakes in operation 100 which otherwise often occur.

Having thus described my invention and the advantages thereof, I do not wish to be limited to the details herein disclosed, otherwise than as set forth in the claims, but what I claim is:— 105

1. Control mechanism for moving-picture apparatus in which two projecting machines are used, each having a motor, sound apparatus and a shutter device, said control mechanism comprising a switching device movable as a unit to successive predetermined positions to render a first machine fully operative to start the motor of a second machine while the first machine remains fully operative, to shift the sound and projection simultaneously to the second machine while leaving the motor of the first machine running, to thereafter stop the motor of the first machine while the second machine continues in full operation, a control lever for said switching device, and an index cooperating with said lever and designating different operative positions of said lever, and a spring plunger in the end of said lever engageable in notches in said index to center and prevent displacement of said lever. 115

2. Control mechanism for moving-picture 120 apparatus in which two projecting machines are used, each having a motor, sound apparatus and a shutter device, said control mechanism comprising a switching device, manually movable as a unit to successive predetermined positions, 125 means effective to render a first machine fully operative when said switch is placed in a predetermined position, means effective to start the motor of a second machine while the first machine remains fully operative when said switch is placed in a second predetermined position, means effective to shift the sound and projection simultaneously to the second machine when said switch is placed in a third predetermined position and while leaving the motor of the first machine 130 running, and means effective to thereafter stop the motor of the first machine when said switch is placed in a fourth predetermined position and while the second machine continues in full operation. 140

3. Control mechanism for moving-picture apparatus in which two projecting machines are used, each having a motor, sound apparatus and a shutter device, said control mechanism comprising a switching device, manually movable as 145

a unit to successive predetermined positions, means effective to render a first machine fully operative when said switch is placed in a predetermined position, means effective to start the 5 motor of a second machine while the first machine remains fully operative when said switch is placed in a second predetermined position, means effective to shift the sound and projection simultaneously to the second machine when said 10 switch is placed in a third predetermined position and while leaving the motor of the first machine running, and means effective to thereafter stop the motor of the first machine when said switch

is placed in a fourth predetermined position and while the second machine continues in full operation, said switching device being further manually movable in either direction to a neutral position beyond said predetermined positions and in 80 which both machines are fully inoperative, and being also movable to an extreme position in either direction, and means to render one or the other of said motors only operative when said switch is in one or the other of said extreme positions. 85
